UNITED STATES PATENT OFFICE.

HARRY FERGUSON, OF NEW YORK, N. Y.

RING FOR UPHOLSTERY, &c.

SPECIFICATION forming part of Letters Patent No. 395,127, dated December 25, 1888.

Application filed May 1, 1888. Serial No. 272,482. (No model.)

To all whom it may concern:

Be it known that I, HARRY FERGUSON, of the city, county, and State of New York, have invented a new and useful Improvement 5 in Metal Rings for Upholstery and other Purposes, of which the following is a specification.

The object of this invention is to obtain a strong and light ornamental metal ring suitable for the suspension of curtains from poles and for other purposes at a small expense by using a superior metal for the exterior surface of the ring and an inferior metal to give the ring the necessary strength.

15 In the accompanying drawings, Figure 1 is a side view of a ring constructed according to my invention. Fig. 2 is an axial section of the same. Fig. 3 is a central sectional view of the hollow metal lining. Fig. 4 is a central sectional view representing the lining as partly formed and illustrating the manufacture of the ring, and Fig. 5 is a corresponding section of the partly-formed shell.

Similar letters of reference designate corresponding parts in all the figures.

A designates the shell of the ring, of brass or other metal; B, the separate hollow lining, of tin-plate or other metal; and C, the eye-wire. The shell and the hollow lining are 30 formed of two rings or annular disks of sheet metal, the ring or disk of which the shell is formed being of larger external diameter and of smaller internal diameter than that of which the lining is formed. The ring or disk 35 of which the lining is to be formed is first struck up, spun, or otherwise brought to the annular trough-like form of transverse section shown at *b b* in Fig. 4 by turning back the inner and outer edges. The edges *b'* are afterward drawn or brought toward each other, as 40 shown in Fig. 3, as close together as practicable.

The ring or disk of which the shell A is formed is struck up, spun, or otherwise brought to the annular trough-like form of transverse section shown at *a* in Fig. 5 by turning back the inner and outer edges *a'*. The hollow lining shown in Fig. 3 is then in-

serted into the trough-like cavity *a*, Fig. 5, of the piece which is to form the shell, with the 50 seam formed by the edges *b'* inward, and the edges *a'* are then turned in over the said lining B and brought close together, as shown in Fig. 2, thus completing the ring, the seam formed by the meeting of the edges *a'* being 55 on the opposite side of the ring to the seam formed by the edges *b'* of the shell. The ring thus composed of the shell A and the inclosed hollow lining B may be made very strong at small expense, because the lining may be of 60 as great a thickness as may be desirable, and the outer shell, A, may be made of very light metal.

The hole for the eye-wire C is formed by drilling or otherwise through the inner and 65 outer sides of the ring, and the eye-wire, not yet having the eye formed in it, but having the head *c* previously formed, is inserted through the said holes from the inside of the ring, and the eye is formed on the outside of 70 the ring after the headed wire has been so inserted through the metal. The wire thus inserted and secured is very firmly attached to the ring and assists in giving stability thereto by securing the shell and lining together. 75

The ring is represented as of circular transverse section; but my invention is not limited to this form of transverse section, as it is obvious that the ring may be made in the same 80 way of any other transverse sectional form.

What I claim as my invention, and desire to secure by Letters Patent, is—

A metal ring composed of a seamed outer tubular shell made of a single piece of metal 85 bent into a ring shape and a separate seamed tubular shell made of a single piece of metal bent into a ring shape and inclosed within said first-named shell, said shells having their seams on different sides of the ring, substantially as specified.

HARRY FERGUSON.
